CLAIM

The ornamental design for a soft tissue anchor, as shown and described.

DESCRIPTION

FIG. 1 is a perspective view of a new design for a soft tissue anchor;

FIG. 2 is a top view thereof;

FIG. 3 is a bottom view thereof;

FIG. 4 is a left side view thereof;

FIG. 5 is a right side view thereof;

FIG. 6 is a back thereof; and,

FIG. 7 is a front view thereof.

The broken line showing portion of a soft tissue anchor is included for illustrating environmental structure and forms no part of the claimed design.
